COMBINATION MERCHANTISING AND DISPLAY
STAND FOR PACKAGED PHARMACEUTICAL SUPPLIES OR THE LIKE

Robert H. Gardner, Moorestown, Kenneth B. Hawthorne,
New Brunswick, and Edward Colton O'Donoghue,
Moorestown, N.J., assignors to Johnson & Johnson, a corporation of New Jersey

Filed Dec. 29, 1959, Ser. No. 58,847

Term of patent 14 years

(Cl. D80—9)

FIG. 1

The dominant features of our design reside in the portions shown in full lines.

We claim:

The ornamental design for a combination merchandising and display stand for packaged pharmaceutical supplies or the like, as shown and described.
